UNITED STATES PATENT OFFICE.

JOHN L. HORVATH, OF FERNGLEN, PENNSYLVANIA.

BRACE FOR BROKEN RAILS

1,030,888.

Specification of Letters Patent. Patented July 2, 1912.

Application filed February 3, 1912. Serial No. 675,183.

To all whom it may concern:

Be it known that I, JOHN L. HORVATH, a citizen of the United States of America, residing at Fernglen, in the county of Luzerne 5 and State of Pennsylvania, have invented certain new and useful Improvements in Braces for Broken Rails, of which the following is a specification, reference being had therein to the accompanying drawing.

10 This invention relates to a brace for broken rails, and more particularly to a device adapted to be temporarily used for holding and bracing the broken ends of a rail.

15 The primary object of my invention is to provide a strong and durable device that can be easily and quickly placed in engagement with a broken rail to preserve the alignment of the broken ends of the rail 20 until a new rail can be installed.

Another object of this invention is to provide a rail chair that can be used in case of emergency for bracing the outer side of the rail and prevent the rail from spreading 25 relatively to the other rail of the track.

A further object of this invention is to provide a simple and inexpensive bond that can be used in connection with a rail chair of the above type for establishing an electric 30 circuit between the broken parts of the rail.

With the above and other objects in view, the invention resides in the novel construction, combination and arrangement of parts to be hereinafter specifically described and 35 then claimed.

Reference will now be had to the drawing, wherein:

Figure 1 is a perspective view of the brace as applied to a rail, Fig. 2 is an end 40 view of the same, and Fig. 3 is a cross sectional view of the same.

The reference numeral 1 denotes a rail chair in the form of a flat rectangular plate that is placed under the base flange 2 of a 45 broken rail 3. The chair is placed to support the broken ends 4 of the rail and at the outer side of the rail there is placed a splice bar 5 to assist in maintaining the alignment of the broken ends of the rail.

50 The inner side of the chair 1, at the ends thereof is cut away, as at 5^a and provided with threaded studs 6 and mounted upon said studs are clamps 7 that are retained thereon by nuts 8. The clamps 7 extend on 55 to the inner base flange of the rail and hold the inner edge of the chair in engagement

therewith. In addition to these clamps there are screw spikes 9 that extend through the openings 10 provided therefor at the inner edge of the chair, said spikes being retained within said openings by nuts 11 screwed upon the lower ends thereof. The heads 12 of the spikes extend on to the inner base flange of the rail and firmly hold the inner edge of the chair in engagement with 60 said rail. The outer edge of the chair, at the ends thereof, has angularly disposed braces 13 engaging under the head of the broken rail, and these braces are provided with screws 14 that engage the web of the 65 rail. The screws 14 are connected by a wire 15, said screws and said wire constituting a bond for electrically connecting the broken 70 ends of the rail.

The outer side of the chair is provided 75 with screw spikes 16 capable of engaging the base 2 of the rail. The outer side of the chair intermediate its ends is provided with vertically disposed bolts 17 upon which are mounted sleeves 18, these latter engaging 80 the chair. Projecting from the splice bar 5 are clamping members 19 having their free ends apertured. The apertured ends of the clamping members 19 are mounted 85 upon the bolts 17 against the sleeves 18 and are fixedly secured in position by nuts 20 which are connected to the bolts 17 and engage the outer ends of the clamping members 19. When the chair is adjusted by shifting the nut 8 the splice bar is carried 90 toward the web for the reason that it is connected to the chair. After the splice bar is secured in position to prevent the shifting 95 of the rail.

The chair 1 supports the broken base of the rail, the spikes 9 and 16 prevent lateral shifting of the rail and the splice bar 5 supports the broken head of the rail.

From the foregoing it will be observed 100 that I have devised a bracing and clamping device that can be easily and quickly installed for retaining the broken ends of a rail in alignment, the device firmly bracing the rail upon the outer side thereof to prevent the broken ends of the rail from spreading relatively to the other rail of the track.

What I claim is:

1. In a bracing device, the combination 110 with a broken rail, of a chair arranged under said rail and having the inner edge

thereof connected to the inner base flange of said rail, angularly disposed braces carried by the outer edge of said chair, at the ends thereof and engaging under the head of said rail, a splice bar arranged against the web of said rail at the outer side thereof, posts carried by said chair, and horizontal clamping members projecting from said splice bar and having the free ends thereof 10 apertured and connected to said posts.

2. In a bracing device, the combination with a broken rail, of a chair arranged under said rail, said chair having the inner edge thereof cut away at the ends thereof 15 and provided with threaded studs, clamps arranged upon the threaded studs of said chair and engaging the inner base flange of said rail, screw spikes carried by the inner

edge of said chair and engaging the inner base flange of said rail, angularly disposed braces carried by the outer edge of said chair at the ends thereof and engaging the under side of the head of said rail, a splice bar arranged against the outer side of said rail, posts carried by the outer edge of said chair, and horizontal clamping members projecting from said splice bar and having the free ends apertured and mounted upon and connected to said posts.

In testimony whereof I affix my signature 30 in the presence of two witnesses.

JOHN L. HORVATH.

Witnesses:

E. A. ROBERTS,
J. G. SINGLEY.
